DISTILLATION OF ACID TREATED OILS

Brian Mead, Houston, Tex., assignor to Standard
Oil Development Company, a corporation of
Delaware

Application August 4, 1933, Serial No. 683,639

9 Claims. (Cl. 196—35)

This invention relates to a process of distilling acid treated oils and will be fully understood from the following description when read in conjunction with the drawing, the sole figure of 5 which is a diagrammatic side elevation partly in section of the apparatus used in carrying it out.

The invention may be used in conjunction with the distillation of various types of mineral oils such as naphthas, petroleum lubricating oils, 10 shale oils, hydrogenated tars or coals, etc., which have been acid treated and which on distillation develop certain undesirable characteristics due to decomposition of compounds containing the acid radical. Since the greatest advantages of the present process are obtained when 15 it is applied to the redistillation of acid treated naphthas, and especially of acid treated cracked naphthas, the same will be described in more detail in conjunction with its last mentioned application.

Redistillation of a cracked naphtha which has been treated with sulphuric acid is the usual method employed for improving the color and lowering the gum and sulphur content of the 20 stock, these changes being effected through removal of polymers. In the course of this distillation, SO_2 is often evolved through the thermal breakdown of sulphuric acid esters present in the acid treated charge. This gas passes out 25 of the still in company with the overhead products, the color of which is impaired by its presence. If, however, a small amount of caustic is added to the charge, the SO_2 is converted to sodium sulphite as rapidly as it is formed and the deleterious effect of the gas on the overhead is thus eliminated. It has been found that the 30 use of caustic in this manner has resulted in an 8 shade Saybolt color improvement in certain instances, the average improvement for a large number of naphthas being approximately 5 shades.

In practice, it has been found advantageous to substitute for the caustic an oil-soluble soap such as the crude sodium naphthenate obtained 35 as a by-product in distilling naphthene base oils over caustic. Corn oil soap, cocoanut oil soap, cotton seed oil soap may be mentioned as examples of other oil-soluble soaps giving good results.

50 The advantages possessed by the soap over caustic are as follows:

(1) Since the material is oil-soluble, much better contact is obtained between the reagent and the SO_2 .

55 (2) It has been found that excessive amounts

of caustic have a deleterious effect on the copper dish gum and breakdown time of the overhead. When caustic is fed to the distillation equipment it is difficult to control its application within such limits that sufficient caustic is provided for reaction with the SO_2 on the one hand while an amount sufficient to adversely affect the gum is not used on the other.

(3) Deposition of inorganic matter on the heating surface of the still is much less in the 10 case where naphthenic soaps are used than when caustic is used.

Although a great number of alkaline bodies such as caustic soda, etc., capable of reacting with SO_2 may be used in our process, the use of 15 oil-soluble soaps is especially contemplated in our invention due to the above enumerated advantages.

Referring now to the figure, the apparatus will be briefly described in conjunction with the 20 method of operating the same.

The acid treated oil from tank 1 and the oil-soluble soaps from tank 2 are passed by means of pumps 3 and 4 through meters 5 and 6 and line 7 into the re-run battery. The oil-soluble soap 25 may be previously dissolved in a solvent such as a heavy lubricating oil. The rerun battery, in case of redistilling naphtha, may consist of tower 8 which is heated by means of a closed steam coil 9 at the bottom thereof. The tower is provided with the usual bell cap plates. All the unvaporized residue is removed through line 11 into residue tank 12. Overhead distillate which leaves the tower through line 13 is condensed in condenser 14 which is connected with a source 30 of vacuum by line 15. The condensed distillate is passed through line 16 by pump 17 to the distillate tank 18. The line 19 serves for the return of reflux condensate to the tower.

The following example will illustrate our process.

A sample of cracked naphtha is treated with 3 pounds per barrel of 98% sulfuric acid by agitation. The acid oil is allowed to settle, is separated from the sludge by decantation then water 45 washed and neutralized with caustic soda. The neutralized oil is then filtered to remove the excess caustic soda and divided into two portions. One portion is distilled under vacuum up to 300° F. final still temperature until 4% bottoms is obtained, the remaining oil being distilled overhead. The other portion is handled in the same manner except that 0.5% by volume of a heavy lube distillate containing about 10% of sodium naphthenate is added to it prior to distillation. Both 50 55

distillates are again divided into two equal portions, the one portion being washed with a sodium carbonate solution and the other being doctor sweetened. The Saybolt colors on the sodium carbonate washed and on the doctor sweetened overheads from the two distillates are the following:

		Sample distilled in the absence of naphthenic soap		Sample distilled over naphthenic soap	
		Carbon- ate washed overhead	Doctor sweet- ened overhead	Carbon- ate washed overhead	Doctor sweet- ened overhead
10					
15					
	Color (Robinson).....	19	20	28	26
	Color after 16 hours exposure at 212° F -----	18	18	25	22

20 Another sample of cracked naphtha is treated with six pounds per barrel of 98% acid and then further treated in an analogous manner. The color inspections are the following:

		Sample distilled in the absence of naphthenic soap		Sample distilled over naphthenic soap	
		Carbon- ate washed	Doctor sweet- ened	Carbon- ate washed	Doctor sweet- ened
25					
30					
	Color (Robinson).....	22	23	27	27
	Color after 16 hours exposure at 212° F -----	20	20	24	22

35 That the SO₂ is largely eliminated from the overhead by the introduction of soap bottoms is evidenced by the following values for the SO₂ present in two samples distilled from the same 40 charge stock, one in the presence and the other in the absence of soap bottoms.

		Sample distilled in absence of soap		Sample distilled in presence of soap	
		Mgms. SO ₂ per liter of overhead.....	67.0	1.4	
45					

50 Reduction of the SO₂ content of the overhead distillate to the extent indicated by the above figures suggests another advantage in using the naphthenate soap products: corrosion of the plant rerun equipment is greatly reduced. Experimental data on plant rerun equipment show that the use of naphthenate soap diminishes the iron loss from 7.18 pounds per day to 0.78 pound per day which corresponds to an 89.2% reduction in corrosion.

55 The present process may be varied in several ways; therefore, it is not to be limited by the above example but only by the following claims in which it is my intention to claim all novelty inherent in the invention.

60 What I claim is:

65 1. The process of distilling an acid treated mineral oil which comprises adding a sufficient quantity of an oil-soluble soap to the oil to practically completely take up any acid-reacting substance evolved from any residue of the treating

acid during the distillation of the oil and carrying out the distillation in the presence of said oil-soluble soap.

2. The process of distilling an acid treated mineral oil which comprises adding a sufficient quantity of an alkali naphthenate to the oil to practically completely take up any acid-reacting substance evolved from any residue of the treating acid during the distillation of the oil and carrying out the distillation in the presence of said alkali naphthenate. 5

3. The process of distilling an acid treated mineral oil which comprises adding a sufficient quantity of sodium naphthenate to the oil to practically completely take up any acid-reacting substance evolved from any residue of the treating acid during the distillation of the oil and carrying out the distillation in the presence of said sodium naphthenate. 15

4. The process of distilling an acid treated petroleum oil which comprises adding a sufficient quantity of an oil-soluble soap to the oil to practically completely take up any acid-reacting substance evolved from any residue of the treating acid during the distillation of the oil and carrying out the distillation in the presence of said oil-soluble soap. 20

5. The process of distilling an acid treated petroleum oil which comprises adding a sufficient quantity of an alkali naphthenate to the oil to practically completely take up any acid-reacting substance evolved from any residue of the treating acid during the distillation of the oil and carrying out the distillation in the presence of said alkali naphthenate. 30

6. The process of distilling an acid treated petroleum oil which comprises adding a sufficient quantity of sodium naphthenate to the oil to practically completely take up any acid-reacting substance evolved from any residue of the treating acid during the distillation of the oil and carrying out the distillation in the presence of said sodium naphthenate. 35

7. The process of distilling an acid treated petroleum naphtha which comprises adding a sufficient quantity of an oil-soluble soap to the naphtha to practically completely take up any acid-reacting substance evolved from any residue of the treating acid during the distillation of the naphtha and carrying out the distillation in the presence of said oil-soluble soap. 40

8. The process of distilling an acid treated petroleum naphtha which comprises adding a sufficient quantity of an alkali naphthenate to the naphtha to practically completely take up any acid-reacting substance evolved from any residue of the treating acid during the distillation of the naphtha and carrying out the distillation in the presence of said alkali naphthenate. 45

9. The process of distilling an acid treated petroleum naphtha which comprises adding a sufficient quantity of sodium naphthenate to the naphtha to practically completely take up any acid-reacting substance evolved from any residue of the treating acid during the distillation of the naphtha and carrying out the distillation in the presence of said sodium naphthenate. 50
